UNITED STATES PATENT OFFICE.

ERNEST LAMORT AND MARCEL LAMORT, OF VITRY-LE-FRANCOIS, FRANCE.

COMBINED CONTROL FOR PURIFYING, SELECTING, SORTING, AND LIKE DRUMS.

Application filed July 15, 1925, Serial No. 43,834, and in France August 8, 1924.

The present invention relates to the construction of combined drives for the operation of purifying selecting, sorting and like drums.

5 It is an observed fact that purifying drums essentially consist of a suitably perforated metallic cylinder which is traversed by a current of water—centrifugal or centripetal—withdrawing the fibres or like substances in suspension, said cylinder or drum being rapidly rotated and also subjected to a sufficiently rapid shaking.

This double movement has hitherto been obtained either by rigid mechanical drives 15 which occasion a considerable noise, and the apparatus is rapidly put out of order, or by the flexible drive according to the patent to Marcel Lamort No. 850,021, April 9th, 1907 entitled: Means for controlling the pulp 20 strainer drums of paper making machines, which drive eliminates the noise and obviates all prejudice to the apparatus, while affording a number of revolutions which is proportional to the number of shocks or oscillations.

The present invention relates to a new drive which utilizes the advantages of the drive set forth in the aforesaid patent, and which further ensures of oscillations and 30 the loading of the machine, and wherein the transfer may be made from the said Lamort flexible drive to the ordinary rigid drive.

Our said drive is essentially characterized in that the belt providing for the oscillations, as set forth in the aforesaid Patent 35 No. 850,021, herein acts not directly upon the flanged end or neck of the purifying drum, but upon an intermediate element, which may be either coupled to the said neck 40 of the drum or uncoupled and made loose, the said neck further comprising a rigid driving member such as a pulley, gear wheel or the like. In this manner the machine may employ the two drives concurrently, or the 45 transfer may be made from one drive to the other according to needs.

Obviously, we may employ various embodiments of the said invention. An embodiment possessing particular advantages is 50 herein set forth by way of example with reference to the appended drawings.

Fig. 1 is an end elevation of our said apparatus, and Fig. 2 a corresponding view 55 in side elevation, partially in section on the main center line.

In the same manner as for the known

types of machine, the purifying drum which is shown in the drawings comprises a suitably perforated cylinder 1 having at one end the flanged portion or neck 2; within the 60 said cylinder is mounted the plate 3 upon which are caused to fall the impurities and like substances to be eliminated. The apparatus comprises all the usual accessory elements such as the feeding conduit 4, the 65 scraper 5 for detaching the impurities and the like from the inner wall of the drum, the vessel 6 for collecting the water charged with fibres and purified material, and the like.

The flexible drive is effected in conformity 70 to the aforesaid patent by means of a belt 7 which is attached at one end to a rod 8 which is stationary when the machine is running but is adjustable in position, and at the other end to a lever 9 which is given a 75 reciprocating motion by any suitable means, for instance a connecting rod 10 and a crank.

The belt 7, instead of passing directly around the flanged portion 2, passes over an intermediate ring 11 which may be secured to the said flanged portion by the 80 screws 12 or by like means. The said flanged portion has also secured thereto in an adequate manner the grooved pulley 13 serving for the ordinary drive by the belt trapezoidal section 14. The said pulley is driven from the main shaft 16 by means of the pulley 15 and a suitable supporting pulley 85 or the like.

When the machine is to be operated upon 90 the flexible drive, as set forth in Patent No. 850,021 it will suffice to slip off the belt 14 and to connect the intermediate ring 11 with the flanged portion 2. In this case the drum is actuated not only with an oscillating 95 movement, but also with a slight rotary movement, as a result of the sticking of the ring to the belt 7. On the contrary, to change over to the ordinary drive, for instance by reason of irregularities due to an 100 overload on the machine. We disengage the ring 11 by releasing the screws 12, and then place the belt 14 in position. When it is desired to operate by the flexible drive, while at the same time being assured that the speed 105 of rotation will in no case descend below the speed of the ordinary drive, or that it will not exceed a maximum rate, the intermediate ring 11 is left in position and the belt 14 in its place, so that the two drives will 110 be simultaneously in operation.

Having now particularly described our

said invention and the manner in which the same is to be performed, we declare that what we claim is:

1. Control device for purifying drums for paper manufacture and the like, comprising, in combination, a drum mounted for rotation, usual drive means for the drum, a flexible drive for the drum, and means to uncouple the flexible drive from the drum.
- 10 2. Control device for purifying drums for paper manufacture and the like, comprising, in combination, a drum mounted for rotation, usual drive means for the drum, a flexible drive for the drum, and means for 15 reducing the effect of the flexible drive at the moment of oscillation of the drum.
- 20 3. Control device for purifying drums for paper manufacture and the like, comprising, in combination, a drum mounted for rotation, usual drive means for the drum, a flexible drive for the drum, the uncoupling means including, a drive flange on the drum, a ring carried by the flange for receiving the

flexible drive, and means on the ring for releasably fixing the ring on the flange.

25 4. Control device for purifying drums for paper manufacture and the like, comprising, in combination, a drum mounted for rotation, usual drive means for the drum, a flexible drive for the drum, the uncoupling means including, a drive flange on the drum, a ring carried by the flange for receiving the 30 flexible drive, and screw means on the ring for releasably fixing the ring on the flange.

35 5. Control device for purifying drums for paper manufacture and the like, comprising, in combination, a drum mounted for rotation, usual drive means for the drum, a flexible drive for the drum, and means rendering the two drives independent of each other.

40 In testimony whereof we have signed our names to this specification.

ERNEST LAMORT.
MARCEL LAMORT.
